VICTOR GRIFFITH, OF SAN FRANCISCO, CALIFORNIA.

INTERNAL-COMBUSTION PUMP.

1,240,967.

Specification of Letters Patent. Patented Sept. 25, 1917.

Application filed January 22, 1917. Serial No. 143,553.

To all whom it may concern:

Be it known that I, VICTOR GRIFFITH, a citizen of the United States, residing at San Francisco, in the county of San Francisco, and State of California, have invented new and useful Improvements in Internal-Combustion Pumps, of which the following is a specification.

The present invention relates to improvements in means for the utilization of heat energy as applied, through its expansive force, in motors, air-compressors and hydraulics.

Most attempts to utilize heat energy in devices of the type directing the explosive energy against liquid pistons have proven abortive through lack of provisions for the exhaust of the products of combustion and for the maintenance of a constant volume for both liquid piston and combustible charge in the combined combustion and displacement chamber.

One object of the invention is to provide means, in a device of the type named, for the positive scavenging of the products of combustion and for the maintenance of constant volume for liquid pistons and combustible charges, so that there may be no encroachment of the one upon the allotted space of the other.

A second object of the invention is to provide a device having provisions for the pre-compression of the combustible charge before its admittance to the combustion chamber, rather than after, thus permitting the utilization of the heavier fuel oils and their combustion at constant pressures.

A third object of the invention is to provide for the purpose named, a device having displacement chambers equal in number to those of the cycles or steps necessary in its operation, these chambers functioning, as to a single cycle or step, in rotation, and yet so coöordinated that the completion of the full cycle by the group of chambers completes also a full cycle for a particular one of the units comprising the group.

In the accompanying drawing, Figure 1 is a side view, partly in longitudinal vertical section of my improved internal combustion pump; Fig. 2 is a similar view, parts being shown in a position different from that in Fig. 1; Fig. 3 is an enlarged cross-section on the line 3—3 of Fig. 2.

Referring to the drawing, 1 indicates a tank or other container of water which is to be pumped, from which leads a pipe 2 controlled by a valve 3 and connected with four branch pipes 4, each provided with a non-return valve 5, and leading to a valve chamber 6, connected with a displacement chamber 7 through an opening 8 controlled by a valve 9 having a valve stem 10 slideable in bearings respectively in a spider 11 extending across said opening 8 and in a casting 12 at the upper end of said displacement chamber. In these four displacement chambers water is forced down in succession by the combustion of gas in a combustion chamber 13 forming an upper extension of the displacement chamber and through a conduit 14 leading past a check valve 15 and into a pipe 16 closed at one end and open at the other, the open end being bent upwardly and extending into the lower end of a valve chamber 17. The water discharged along said pipe 16 by the pressure in each displacement chamber 7 emerges from said open end of the pipe 16, and forces upwardly a slide valve 18 slideable in the valve chamber 17 and having a transverse web 20 secured by nuts 21 to the lower end of a valve stem 22 which slides through a bearing in the upper end of the valve casing 19 and is attached to the lower end of a differential piston 23. When said valve 18 has been pressed upward a sufficient distance, water escapes from the lower portion of said valve chamber into a pipe 24, controlled by a valve 25, and opening upwardly past a non-return valve 26 into a compression chamber 27. From the lower portion of said compression chamber a discharge pipe 28 leads upwardly and is controlled by a valve 29. Said compression chamber communicates by a conduit 30 with the upper portion of the valve chamber 17 so that said upper portion is always under the same pressure as that in the compression chamber 27.

By reason of the above-described construction, with each explosion in any one of the four combustion chambers 13, the valve 18 is raised to raise the differential piston, and between the successive explosions the valve 18 descends again under the combined pressure in the valve chamber and the pressure of a spring 31 coiled around the stem 22 and

compressed between the upper end of the valve casing and the web 20.

In order to permit the differential piston to return to its lowermost position, which would be impossible otherwise on account of the water in the lower end of the valve chamber 17 and in the pipe 16, there is provided an air chamber 32 communicating at the bottom by a pipe 33 with the open end of the pipe 16. There is also provided in this chamber a spring-controlled inlet valve 34, through which, when the pressure becomes less than atmospheric, air will be admitted by reason of the injection effect of the water flowing at high velocity in the open end of the pipe 16 around the open end of the pipe 33.

The larger end of the differential piston on its downward stroke draws in air through a check valve 35 and expels it through a pipe 36 having therein a check valve 37, a safety valve 38, a gage 39 and discharging into a compressed air cylinder 40. A conduit 41, controlled by a valve 42, leads from said compressed air cylinder and has a contracted nozzle 43 discharging into a conduit 44. From a contracted portion 45 of said conduit 41 leads a pipe 46, having therein a controlling valve 47, and discharging into the upper portion of a gasoline or other fluid fuel chamber 48. From the lower portion of said chamber leads a pipe 49, having therein a controlling valve 51 and discharging into the center of said contracted nozzle. By means of the velocity of said compressed air issuing from said compressed air chamber and surrounding the discharge end of the pipe 49, and also by reason of the pressure of said air upon the surface of the gasoline in the chamber 48, gasoline vapor is forced out of said open end of the pipe 49, and is thoroughly mixed with the air emerging from said nozzle, and is conducted by a conduit 52 to a chamber 53, from which branch conduits 54 lead to valve casings 55 at the heads of the respective combustion chambers in which are rotary valves 56. Said valves are attached at one end to crank arms 57, each connected to one end of a link 58, the other ends of said links being connected to U-cranks 59 on a shaft 60 rotating in bearings 61. Said shaft is rotated by means of a rack 62, carried by the valve stem 22 and engaging a gear wheel 63 loose on said shaft 60 and carrying a pawl 64 which engages a pinion 65 fast on said shaft 60. The dimensions of the rack and gear wheel are such that, with each reciprocation of the rack, the gear wheel 63 and shaft 60 are rotated one-quarter of a revolution. By this means all of said valves are intermittently rotated through one-quarter of a revolution with each complete reciprocation of the valve stem 22 and each branch conduit 54 is in

communication with the corresponding combustion chamber 13 once in each revolution of the shaft 22.

In said combustion chamber is a spark plug 64 in a circuit 65 closed once in each revolution of the shaft by means of a contact ring 66 on said shaft 60. Thereby the carbureted air is ignited, and combustion thereof takes place, driving a water piston downward in the displacement chamber. When the products of combustion are expanded as fully as is permitted by the back pressure in the pipe 16, the check valve 15 is closed, and, at the same time, by means of a cam 67 upon the shaft 60 a valve 68 is opened, permitting the gases to escape by a branch conduit 69 into a conduit 70, which is inclosed within the chamber 53, a conduit 71 leading from said conduit 70 through the wall of said chamber into the atmosphere.

A float 72 is guided by the valve stem 10 and abuts in its upper position against a stop 73 on said stem, and descends with the water in the displacement chamber until it abuts against a stop 74 on the lower portion of said valve stem. Then the farther descent of said float has the effect of opening the valve 9, thereby admitting water from the source of supply. Then water rises in the displacement chamber, thereby forcing out the burnt gases therefrom, which scavenging action is assisted by air admitted through a check valve 75 into a cylinder 76 surrounding the smaller end of the differential piston 23 upon the upward stroke of said piston, and, upon the downward stroke of the piston forced out of said cylinder 76 into a pipe 77, having therein a check valve 78, and thence into branch pipes 79, each having therein a check valve 80 and opening into the corresponding combustion chamber. By both of these means, the hot products of combustion are forced outward from the combustion chamber through the valve 68 and branch conduit 69 into the conduits 70 and 71, thereby heating the carbureted air in the chamber 53 surrounding said conduits. The flow of water into the displacement chamber is arrested when the float valve 72, having abutted against the upper stop 73 upon the valve stem 10, then raises said valve stem so as to close the valve 19 to its seat. In this way the volume of water admitted into the displacement chamber is always the same for each cylinder.

I claim:

1. In an apparatus of the character described, the combination with a series of internal combustion chambers, having electrically ignited spark plugs, liquid outlet pipes leading therefrom, a common pipe into which they discharge, a pressure chamber, a valve actuated by the pressure of liquid in said common pipe, and controlling the communication between said common

5 pipe and the pressure chamber, a shaft actuated by said valve, and means, actuated by said shaft, for controlling the circuits through the spark plugs of the internal combustion engines.

10 2. In an apparatus of the character described, the combination of a series of internal combustion chambers, liquid outlet pipes leading therefrom, a common pipe into which they discharge, a pressure chamber, a valve actuated by pressure of liquid in said common pipe, and controlling the communication between said common pipe and the pressure chamber, a shaft actuated by said valve, and means, actuated by said shaft, for controlling the admission of fluid fuel into said combustion chambers.

15 3. In an apparatus of the character described, the combination of a series of internal combustion chambers, liquid outlet pipes leading therefrom, a common pipe into which they discharge, a pressure chamber, a valve actuated by the pressure of the liquid in said common pipe, and controlling the communication between said common pipe and the pressure chamber, a shaft actuated by said valve, and means actuated by said shaft, for controlling the exhaust from said internal combustion chambers.

20 4. In an apparatus of the character described, the combination of a series of internal combustion chambers, liquid outlet pipes leading therefrom, a common pipe into which they discharge, a pressure chamber, a valve actuated by the pressure of the liquid in said common pipe and controlling the communication between said common pipe and the pressure chamber and a piston, actuated by said valve, for forcing carbureted air into said cylinders and for exhausting waste gases therefrom.

25 5. In an apparatus of the character described, the combination of a series of internal combustion chambers, liquid outlet pipes leading therefrom, a common pipe into which they discharge, a pressure chamber, a valve actuated by the pressure of liquid in

said common pipe, and controlling the communication between said common pipe and the pressure chamber and a differential piston, actuated by said valve for forcing carbureted air into said cylinders and for exhausting waste gases therefrom. 50

30 6. In an apparatus of the character described, the combination of a series of internal combustion chambers, liquid outlet pipes leading therefrom, a common pipe into which they discharge, a pressure chamber, a valve actuated by the pressure of liquid in said common pipe and controlling the communication between said common pipe and the pressure chamber, a piston, actuated by said valve, for forcing carbureted air into said cylinders and for exhausting waste gases therefrom, a relief chamber, and 55 a pipe communicating with said common pipe and leading to said relief chamber. 60

35 7. In an apparatus of the character described, the combination of an internal combustion chamber, an inlet conduit for supplying liquid to the lower portion of said chamber, means for igniting combustible fluid fuel in the upper portion of said chamber, a valve for limiting the amount of water admitted to said internal combustion chamber through said inlet pipe, and 70 a float operating by its buoyancy to close said valve. 75

40 8. In an apparatus of the character described, the combination of an internal combustion chamber, an inlet conduit for supplying liquid to the lower portion of said chamber, means for igniting combustible fluid fuel in the upper portion of said chamber, a valve for closing the communication 80 between said internal combustion chamber and the inlet conduit, a vertically movable stem operatively connected to said valve, upper and lower stops thereon, and a float 85 slideable on said stem between said stops and operating by its buoyancy to close said valve. 90
